FABRIC STRETCHING AND STRAIGHTENING APPARATUS

Paul A. Sperry, New Haven, Conn.

Application March 11, 1937, Serial No. 130,351

1 Claim. (Cl. 26—54)

This invention relates to cloth-stretching mechanisms, and in particular to an apparatus for opening out a web of moving fabric or cloth from rope-like form to straighten out the same and provide a smooth web free from wrinkles, puckles or folds along the edge of the cloth by the use of simple mechanical means.

Another object of the invention is the provision of a reel for delivering a length of cloth in rope-form to a pair of feed rollers and with guide rolls for use in opening out and also guiding the cloth from rope-like form into a straightened condition as it is inserted and passed between the feed rollers.

Another object of the invention is the provision of a device for opening the cloth which will act diagonally thereon in a very simple and efficient manner, while the cloth is travelling to and through the feeding rolls so that a continuous straightening operation may be performed.

Another object of the invention is the use of guide rolls instead of scutchers, thereby using a more simple and less expensive apparatus for accomplishing the desired operation.

With these and other objects in view, the invention consists of certain novel features of construction, as will be more fully described, and particularly pointed out in the appended claim.

In the accompanying drawings:

Fig. 1 is a front view showing a fragmental portion of a straightened web of cloth showing my guiders arranged in position for holding the opposite marginal edge portions thereof to maintain the cloth in a stretched-out condition;

Fig. 2 is a perspective view showing diagrammatically the reel and feed rollers in operating relationship and embodying my guide and opening means; and

Fig. 3 is a perspective view of one of my guiders and opener members.

In certain textile operations, it is desirable to cause an opening-out and straightening of the fabric while it is in motion and from a rope-like condition into a straightened smooth web as it is being continually moved in a rectilineal direction for the performance of various subsequent operations as it is being processed and without stopping the cloth; heretofore scutchers were used in this operation; and in order to accomplish this result in a simple manner, I have provided a cloth opening and straightening mechanism comprising a reel around which the fabric or cloth in rope form is conveyed, and from which it is delivered at right angles to the reel across a considerable distance to a pair of feed rollers

and from thence on to a tenter or some other machine, and in order that the cloth will be inserted and drawn between the feed rolls in a smooth, straightened, un wrinkled condition I have provided a pair of guide rolls adjacent to 5 and in advance of the feed rolls and disposed above and beneath the surfaces of the cloth for engaging the opposite borders thereof, with the axes of each pair of the guide rolls inclined at an angle to the direction of motion of the cloth 10 to grip and move it outwardly. The rolls are operated by a fluid actuated mechanism connected with one of the rolls of each pair in order to cause engagement and release of the cloth to impart a nip thereto so that as they 15 rotate in unison on their inclined axes their surfaces act to exert a pull on the margins or borders of the cloth in substantially a transverse direction of the latter as it advances to transversely stretch the same and thus straighten out 20 the cloth and free the latter from its rope formation, thus eliminating the use of the heretofore more complicated mechanism at this location and obtaining an equivalent satisfactory result; and the following is a more detailed description of the present embodiment of this invention, illustrating the preferred means by 25 which these advantageous results may be accomplished:

With reference to the drawings, 10 designates 30 a reel mounted to rotate about a horizontal axis, shown as shaft 11 mounted in suitable bearings in the spaced hangers 12 which are supported in a depending position from the ceiling, beams or other convenient parts of the building. A pulley 13 is fixed on the outer end of the shaft 11 of the reel 10 and serves to transmit the driving power for rotating the reel. Also depending from the ceiling of the building is the frame 15 having spaced upright members 16, one of which 40 carries a pair of rings or pot eyes 17 which are mounted to conveniently guide the rope to the reel here shown with their axes at right angles and located in the same vertical plane. The pot eyes 17 may be made of any hard, smooth material, such as porcelain or other well-known, wear-resisting material which will present a smooth surface.

As shown in Fig. 2, the cloth 18 in its twisted or "roped" form is drawn up through the opening of the pot eyes 17 and passes around an upright 19 secured to the frame 15, then up and around the reel 10 from which it is drawn in a direction at right angles to the axis of the reel and extends for a considerable rectilineal dis- 55

tance in a long span, which may often be some thirty or forty feet, to a feeding device 20 having a pair of power driven feed rollers 21 and 22. The reel 10 and the rollers 21 and 22 of the feeding device 20 are mounted to rotate about axes so related as to be disposed along substantially parallel lines. The cloth is opened out and straightened during its passage.

As shown in Fig. 1, the feed rollers 21 and 22 10 are suitably mounted for rotation upon parallel axes, or shafts (not shown) which are journaled in suitable bearings in the spaced hangers 24 and 25 suspended from the ceiling of the room, the cloth 18 being inserted and passed between 15 the feed rollers in a straightened condition.

In advance of the feed rollers 21 and 22, I have provided guide rollers 26, 27, 28 and 29, arranged in pairs and oppositely disposed across the moving cloth for engaging the opposite edges thereof. Each pair of guide rolls 26, 27, 28 and 29 20 are inclined diagonally or set at an angle to the surface of the cloth and extend transversely thereof in the direction of feed of the fabric through the feed rollers 21 and 22 so as to grip 25 and laterally spread and stretch the cloth to untwist the same. The pairs of guide rolls 26, 27 and 28, 29 respectively, are mounted in a hinged frame 30 which is moved by a fluid pressure device 31 having a diaphragm 32 automatically controlled by a feeler mechanism 33 which engages an edge of the moving fabric and so arranged that should the fabric run off a small amount from center one of the pairs of guide rolls will be rendered inoperative and caused to open up 35 sufficiently to release their grip on the selvage edge of the cloth while allowing the other pair of guide rolls to transversely pull the cloth back into centralized position with respect to the longitudinal axis of the feed rolls. A guider device 40 of this character may be constructed as shown and described in more detail in my co-pending application, Serial No. 88,585, filed July 2, 1936, which became U. S. Patent No. 2,170,578.

These roll units by being located on the frame-

work of the feed rolls heretofore described and being sufficiently sensitive to operate quickly and cause a firm grip of the fabric, serve to open out the fabric to its desired extent and which assisted somewhat by the length of travel and weight of the fabric also guide the fabric so that a substantial center line of feed may be maintained, and as far as I know, the location of these guiding and gripping rolls 26, 27, 28 and 29 for the purpose of serving to open out and also guide 10 the fabric as it is delivered in rope form has never heretofore been done, but instead scutchers have been used for this purpose, the scutchers being a much more expensive apparatus than the simple guider rolls which are utilized in this 15 connection.

The foregoing description is directed solely towards the construction illustrated, but I desire it to be understood that I reserve the privilege of resorting to all the mechanical changes to 20 which the device is susceptible, the invention being defined and limited only by the terms of the appended claim.

I claim:

A flat web fabric stretching and straightening apparatus comprising a reel, means for guiding the fabric in rope-form to said reel so as to conduct the fabric over said reel, means for rotating said reel, power driven feed rolls between which the fabric is passed positioned at a sufficient distance from said reel to provide a substantial sag in the fabric without support therebetween to partially open the rope formation thereof to a substantially flat web formation, a pair of guide rolls adjacent to said feed rolls and in advance 35 thereof, said guide rolls being mounted for rotation on axes which are inclined diagonally in the direction of the movement of the fabric and movable toward and from each other to engage and grip the opposite marginal selvage surfaces 40 of the moving fabric and pull the same laterally, so as to completely straighten out the moving fabric by exerting a transverse pull thereon.

PAUL A. SPERRY.
